UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF CANADA.

MANIFOLDING SALES-BOOK.

1,158,889.

Specification of Letters Patent.

Patented Nov. 2, 1915.

Application filed November 22, 1911. Serial No. 661,708.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to 10 which it appertains to make and use the same.

This invention relates to salesbooks.

One of the objects of the present invention is to provide a simple and practical 15 manifolding salesbook.

Another object is to provide a salesbook of the above character which will be inexpensive to manufacture and durable in construction.

20 A further object is to provide a compact and self-contained salesbook permitting of ready and rapid manipulation of the carbon sheet.

Another and important object is to provide 25 a carbon-sheet-holding arrangement which will be manipulated by grasping the upper end of the salesbook and applying transverse pressure to the holding means between the thumb and fingers of the grasping hand.

Other objects will be in part obvious and in part pointed out hereinafter.

The invention accordingly consists in the 35 features of construction, combinations of elements and arrangement of parts which will be exemplified in the construction hereinafter set forth, and the scope of the application of which will be indicated in the following claims.

40 In the accompanying drawing, wherein is shown one of various possible embodiments of this invention, — Figure 1 is a perspective view showing a portion of a salesbook with parts of the paper broken away 45 to more clearly show certain features of construction; Fig. 2 is an end elevation of the book in normal position; Fig. 3 is a similar view, showing the carbon holder raised; and Fig. 4 is a side elevation of a portion of the book.

Similar reference characters refer to similar parts throughout the different views of the drawing.

55 Referring to the accompanying drawing, and particularly to Fig. 1, a back 1 sup-

ports a pad 2 firmly clamped in operative position therewith by means of a pad holder. The pad as herein shown is composed of a plurality of sets of original and duplicate leaves. The pad holder comprises a base 3 secured to the back 1 by means of rivets 4 and is provided with an integral upwardly extending portion 5 to which a top clamping member 6 is hinged along its rear edge. Suitable springs 7 associated with the hinge 60 force the member 6 downward into clamping position. Made from an integral extension of the base 4 is a guard member 8 in the form of a flattened cone through which passes a rod 9 carrying a clamp 10 65 for the carbon sheet extending transversely across the pad 2. This guard 8 not only acts in keeping the thumb out of contact with the rod 9, thereby permitting a free 70 turning or pivotal movement thereof, but also acts as a guide for the rod 9 in its up-and-down movement as the pad varies in thickness. The clamp 10 is adapted to secure an end edge of a carbon sheet 11 and hold the sheet in operative position normally lying between the leaves of the pad. By constructing these parts in the manner described, the cost of manufacture and time 75 in assembling are greatly reduced.

The rear end of the rod 9 is provided 80 with a crank arm 12, as better shown in Figs. 2 and 3. A pin 13 on the crank arm 12 engages one end of a second rod 14 passing through a suitable guide member 15 secured to the back of the pad. At the opposite end of the rod 14 is a push button 16 85 forming one abutment for a spiral spring 17, the other end of the spring engaging the guide 15; the spring is compressed when the button is actuated. The crank 12 and 90 rod 14, the latter constituting a pitman, are arranged slightly off center, so that by pushing on the button 16 the crank 12 will turn about an axis transverse to its length through substantially 90 degrees to the 95 actuated position shown in Fig. 3, thus raising the carbon holder or clamp 10 to a vertical position and removing the carbon sheet 100 from between the set of leaves of the pad then in use. On such operation the spring 105 17 is compressed, the corner of the back 1 being cut away at 18 to permit necessary movement, and on releasing the push button 16 the spring expands to return the parts to normal position. By having the 110

crank arm and rod 14 arranged almost in a dead center position, the carbon sheet is given a sudden snap at first, thereby more quickly and efficiently removing the sheet 5 from its operative position beneath the top or original leaf of the set. It is also to be noted that by constructing the guard member 8 in the manner shown and described, the arm 3 is permitted to move freely up 10 and down in a vertical plane to accommodate the clamp 10 to the varying thickness of the pad as it is used.

The manner of operating the device is substantially as follows: After inserting a 15 new pad in the pad holder it is turned back in the manner shown in Fig. 1 and the top sheet of the bottom set is raised and the carbon sheet with the clamp 10 is inserted between the original and duplicate sheets 20 in a well-known manner. After recording the transaction the button 16, at the right side of the pad within convenient reach of the forefinger of the left hand supporting the pad, is firmly pressed, to move the rod 25 or pitman 14 longitudinally, causing the holder to swing suddenly upward about the axis of the arm 9, thus separating the leaves and permitting the original leaf to be more readily torn from the pad, the duplicate leaf 30 remaining on file at the bottom of the book and concealed by the subsequently used sets. The second duplicate leaf is then swung downward to receive the carbon sheet when 35 the push button is released, and the second original sheet placed thereover. The device is then ready for the second operation. As shown in Fig. 1, several duplicate leaves 19 are shown in filed position at the bottom of 40 the pad, with a set of original and duplicate leaves 20 and 21, respectively, in operative position with the carbon sheet or manifolding material therebetween.

As the pad 2 becomes gradually reduced in thickness, the clamp 10 automatically 45 rises to its new position, swinging about the axis of the rod 14, thus normally lying flat between the leaves of the pad, regardless of its thickness. In other words, the clamp has a compound movement about two axes 50 positioned at substantially right angles to each other.

From the above description it will be seen that this invention provides a simple and practical form of manifolding sales-book, accomplishing, among others, all of 55 the objects and advantages above set forth.

As many changes could be made in the above construction and many apparently 60 widely different embodiments of this invention could be made without departing from the scope thereof, it is intended that all matter contained in the above description or shown in the accompanying drawing shall be interpreted as illustrative and 65 not in a limiting sense.

Having described my invention, what I claim as new and desire to secure by Letters-Patent is:

1. In a manifolding sales-book, a pad, a 70 pad-holder, a carbon sheet, and a carbon-sheet holding and operating device, comprising a clamp for the sheet, a rod connected for raising and lowering the clamp, a guard preventing interference with the motion of the rod by the hand which grasps the 75 sales-book, and means, operated by grasping the upper part of the sales-book, for raising and lowering the rod, thereby raising and lowering the carbon-sheet, as described.

2. In a manifolding sales-book, a pad, a 80 pad-holder, a carbon sheet and a carbon-sheet holding and operating device, comprising a clamp for the sheet, a rod connected for lifting and lowering the clamp, a guard over the rod which prevents interference with the motion of the rod, a crank on the end of the rod, a pitman operating the crank and extending across the top of the sales-book, and a spring for returning the pitman to its normal position after the 85 device has been operated; whereby pressure upon the end of the pitman will revolve the crank and raise the clamp containing the carbon-sheet, such pressure being applied by grasping the top of the sales-book, substantially as set forth.

3. A carbon-sheet holding and operating device for a manifolding sales-book, comprising a clamp, a rod connected for lifting the clamp when the rod is turned about its 100 axis, a crank on the end of the rod for turning it, a pitman connected to the crank, and a spring for returning the pitman to place; whereby pressure upon the end of the pitman will act to snap the clamp suddenly 105 upward and thus displace the leaves of the sales-book and withdraw the carbon sheet from between them, while the spring, after the pressure is released, returns the pitman to its normal position, thus lowering the carbon sheet into place; the action of the device being controlled by grasping the upper end of the sales-book and applying pressure to the pitman, or not, as required.

4. In a manifolding salesbook, in combination, a pad, a pad-holder therefor, a carbon sheet adapted to be interposed between the leaves of said pad, a carbon holder therefor connected with said pad-holder, said carbon holder being loosely mounted to move 110 in a substantially vertical direction as the pad varies in thickness, and means for guarding said holder in its vertical movement.

5. In a manifolding salesbook, in combination, a pad, a pad holder therefor, a carbon sheet adapted to be interposed between the leaves of said pad, a carbon holder therefor, said carbon holder being loosely mounted to move in a substantially vertical direction as 115

the pad varies in thickness, and means for guarding said holder in its vertical movement, said means being formed from an integral turned-up end of said pad holder.

6. In a manifolding salesbook, in combination, a pad, a pad holder therefor, a carbon sheet adapted to be interposed between the leaves of said pad, a carbon holder therefor, said holder being pivotally mounted to 10 swing about one end as an axis, and means for guarding said holder in its movement against interference, said means being in the form of a flattened cone and being constructed from the turned over integral end 15 of said pad holder.

7. In a manifolding salesbook, in combi-

nation, a pad holder, a carbon holder directly connected therewith, pivotally mounted to have a swinging movement in two directions about its connection with said pad holder, and a guard for said carbon holder formed from an integral part of said pad holder adapted to prevent the hand of the operator from interfering with the movements of said carbon holder. 20 25

In testimony whereof I affix my signature, in the presence of two witnesses.

EDWARD KIRBY BOTTLE.
